Non-Final Office Action, U.S. Appl. No. 15/090,233, dated May 30, 2017.

Primary Examiner — Celia Murphy*Assistant Examiner* — Clare Ann Gannon(74) *Attorney, Agent, or Firm* — Polsinelli PC(57) **CLAIM**

The ornamental design for a personal sampling belt, as shown and described.

DESCRIPTION

FIG. 1 is a perspective view of a personal sampling belt showing our new design.

FIG. 2 is a front view of the personal sampling belt.

FIG. 3 is a back view of the personal sampling belt.

FIG. 4 is a right side view of the personal sampling belt.

FIG. 5 is a left side view of the personal sampling belt.

FIG. 6 is a top view of the personal sampling belt; and,

FIG. 7 is a bottom view of the personal sampling belt.

The broken lines shown in the Figures are environment only and form no part of the claimed design.

1 Claim, 4 Drawing Sheets(56)
